UNITED STATES PATENT OFFICE.

WALTER S. EDMANDS, OF BOSTON, MASSACHUSETTS.

ICE-CREAM FREEZER.

1,414,727.

Specification of Letters Patent. Patented May 2, 1922.

Application filed April 2, 1921. Serial No. 457,880.

To all whom it may concern:

Be it known that I, WALTER S. EDMANDS, a citizen of the United States, residing at Boston, county of Suffolk, State of Massachusetts, have invented a certain new and useful Improvement in Ice-Cream Freezers, of which the following is a specification, reference being had therein to the accompanying drawings.

- 10 The invention relates to an improvement in ice cream freezers. One object of the invention is to provide a power driven ice cream freezer in combination with a cabinet having a cover, and means whereby when the 15 cover is closed it will automatically start the freezer and when the cover is open it will automatically stop the operation of the freezer. Another object of the invention is to provide the freezer with a cabinet 20 which entirely covers and protects all of the mechanism during the operation of the freezer. Other features of the invention will be more particularly pointed out in the claims.
- 25 The invention will be fully understood from the following description when taken in connection with the accompanying drawings, and the novel features thereof will be pointed out and clearly defined in the claims 30 at the close of this specification.

In the drawings, Fig. 1 is a side elevation of a freezer embodying the invention, showing the cover closed and the parts in operative position for driving the freezer.

Fig. 2 is a side elevation showing the cover turned up on its hinge, the hinged top of the cabinet being closed.

Fig. 3 is a front elevation partly broken away of the parts shown in Figure 1.

- 40 Fig. 4 is a detail view of the contact mechanism.

Fig. 5 shows a modification of the means for starting and stopping the machine.

Referring now to the drawings, 1 is the 45 tub of an ice cream freezer which is mounted in a cabinet case 2, preferably metal, having a base 3 and legs 4. It is to be noted that the base 3 has an extension 5 on one side to counterbalance the weight of the cover when 50 the cover is turned back on its hinge, as will be hereinafter described.

The freezer and case are provided with guides to maintain the freezer tub 1 in proper position within the case. Any suitable guides may be provided. As shown in

the drawings, one side of the freezer tub is provided with angle irons 6 secured to the sides thereof, each having a downwardly extending pin 7 which engages a hole in the flange 8 of an annular angle iron secured to 60 the inner periphery of the case 2. Any suitable guide, however, may be employed in lieu of the form above described.

The case extends slightly above the top of the tub and is provided with a top 11 hinged 65 at 12 to the top of the case, so that said top 11 may be swung open, as shown in Figure 2. Said hinged top is provided with a spring catch 13 which, when said top is closed, engages with a projection on the side 70 of the case opposite the hinge to hold the top in closed position.

A yielding member 15 is provided on the under side of said hinged top 11 which engages the top of the freezer when the said 75 top is closed to maintain a yielding pressure on the freezer. This member 15 is preferably a pad of suitable compressible material. The paddle shaft 16 of the freezer has suitable gear connection with the counter shaft 80 17, said gear connection shown consisting of a beveled gear 18 on the shaft 16 engaging with a beveled gear 19 on the counter shaft 17. Said counter shaft 17 carries a spur gear 20 which projects up through a slot 21 85 in the hinged top member 11.

Mounted on the upper side of said hinged top 11 is an electric motor 22 having a shaft 23 provided with a pinion 24 which meshes with the gear 20 on the counter shaft 17. 90 Said motor shaft 23 is driven in the well-known manner by an electric motor. As shown in the drawings, the current of the motor is introduced by means of an electric cable 25 through an insulated bushing 26 95 mounted on a metallic bracket 27 secured to the upper side of said hinged top 11; thence the current passes through the wires 28 and 29 to the positive and negative poles of a switch within a box 30 mounted fast on the 100 hinged top 11. The wire 29 leads to the contact member 31 within said box and the wire 28 is connected with the binding post 32 in the box with which is connected an armature spring 33 carrying a contact member 34. 105

A cover 35 is hinged at 36 to the hinged top 11, said cover 35 having preferably an arched top, as shown, and flat parallel sides 37.

Secured to the inside of the case 1 near 110

the top is a strike member 38 which is shown as being in the form of an angle iron and which, when the top 11 is closed, is engaged by the lower end of the contact member 34, 5 and the spring 33 yields to allow the contact member 34 to be forced up into engagement with the contact member 31, thus closing the circuit and starting the motor. When said hinged top 11 is thrown open, the spring 33 10 opens the contact automatically and stops the motor. The cover is provided with spring catches 39 which engage with projections 40 on the case to hold it closed, but the spring catches will readily yield to be disengaged whenever it is desired to turn the cover back on its hinge. The hinged top 11 is provided with a handle 41 for convenience in turning it back on its hinge to open it, and in so doing, it will also carry with it the 15 cover 35. If desired, the cover 35 can be turned back independently of the hinged top 11.

In order to conveniently hold the cover 35 and top 11 in their open position, there is 25 provided a bar 42 pivoted at 43 to the side of the top 11, and said bar is provided near its lower end with a series of notches 44 which are adapted to engage with a pin 45 which projects from the side of the case so 30 that the top 11 and the cover 35 may be maintained in such open position as desired by engaging one of the notches of the said bar 42 with the said pin 45.

The hinged cover 35 may be opened and 35 closed independently of the hinged top 11, but if when the cover 35 is in closed position, the top 11 is opened, it will carry with it the hinged cover, so that only one action is required to open them both and stop the motor.

40 In the modification shown in Figure 5, there is shown a construction whereby instead of having the electrical contact made to start the motor by closing the hinged top 11, the contact is made only by closing the 45 hinged outer cover 35. In the form of construction previously described, the motor will be started if the hinged top 11 is closed, even if the hinged cover 35 is left open. This will leave exposed the motor and the 50 portions of the mechanism mounted on top of the hinged top 11 while the machine is running. It may be deemed desirable, therefore, by some users of the machine to have the machine operated only when the top 55 cover 35 is closed. In Figure 5, there is shown a construction whereby the contact is made and broken by the opening and closing of the cover 35 irrespective of the hinged top 11 still being closed. In this form of construction there is mounted on the hinged cover 35 a lug 46 which, when the said cover is closed, presses down on the contact member 34 which, in this case, is in inverted position from that shown in Figure 4, and 60 closes the switch to make the circuit. When 65

the hinged cover 35 is thrown open, the spring 33 opens the contact automatically and stops the motor.

I have referred to the member 11 as a hinged top and to the member 35 as a hinged 70 cover, more particularly for convenience of designation in the particular description of the two members. As a matter of fact each one of them is a cover, the member 35 merely serving as a supplementary cover, and as 75 already pointed out, the arrangement of the contact member may be such that the electrical contact for starting the machine may be made by closing the hinged member 11 or it may be so arranged that the electrical 80 contact is made by closing the hinged member 35. I regard both of these forms of construction and arrangement as coming within the scope of the invention, and wherever applicable in the claims the use of the 85 term "cover" is intended broadly to include either the hinged member 11 or the hinged member 35, or any other form of movable top closing member, as I believe that I am the first to devise a freezer having a motor 90 which is automatically started by closing a top or cover member and which is automatically stopped by opening the top or cover member.

What I claim is:—

95 1. In combination with a rotary work shaft, a mount for said work shaft, a hinged lid above said shaft, an electric motor mounted on said lid, means whereby when said lid is closed, said motor makes driving connection with said work shaft, an electric circuit for energizing said motor, and contact mechanism which is broken by the opening of said lid and closed by the closing of said lid. 100

105 2. In combination with a rotary work shaft, a countershaft having driving connection therewith, a mount for said work shaft, a lid hinged to said mount above said shaft, an electric motor mounted on said lid having a shaft driven thereby, means whereby when said lid is closed said motor shaft makes driving connection with said countershaft, an electric circuit for energizing said motor, and contact mechanism mounted in 110 the lid which is broken by the opening of the said lid and closed by the closing of said lid. 115

120 3. In combination with a rotary work shaft, a casing therefor having a hinged lid, an electric motor mounted on said hinged lid, driving connection between said motor and said work shaft, means mounted in the lid whereby the closing of the said hinged lid closes the electric circuit which starts the motor, said circuit being broken by the opening of the lid. 125

130 4. In combination with a rotary work shaft, a countershaft having driving connection with said work shaft, a gear mounted on said countershaft, a casing in which said

work shaft is mounted, a lid hinged to said casing, an electric motor mounted on said lid having a shaft driven thereby, a gear mounted on said motor shaft which when the said 5 lid is closed makes driving connection with the gear on said countershaft and which is disengaged when the lid is opened, and contact mechanism mounted in said lid which is closed by the closing of the lid to start 10 the motor, and which is opened to stop the motor when the lid is opened.

5. In combination with a rotary work shaft, a countershaft having driving connection with said work shaft, a casing in 15 which said work shaft is mounted, a lid

hinged to said casing, an electric motor mounted on said lid having a shaft driven thereby, contact mechanism mounted in said lid which is closed by the closing of the lid to start the motor and which is opened thereby stopping the motor when the lid is opened, and driving connection between said motor shaft and said countershaft which is rendered operative to drive the countershaft when the said lid is closed, and which is disengaged from driving connection with the motor shaft when the lid is opened. 20 25

In testimony whereof I affix my signature.

WALTER S. EDMANDS.
